[57] **CLAIM**

The ornamental design for a hub flange for clutch especially for automotive racing applications, as shown and described.

DESCRIPTION

FIG. 1 is a front elevational view illustrating a hub flange for a clutch, especially for automotive racing applications in accordance with my new design;

FIG. 2 is a rear elevational view of the hub flange illustrated in FIG. 1;

FIG. 3 is a longitudinal cross-sectional view of the hub flange illustrated in FIGS. 1 and 2, taken along section lines 3—3 of FIG. 1; and,

FIG. 4 is a side elevational view of the hub flange illustrated in FIGS. 1-3.
